UNITED STATES PATENT OFFICE.

HOLLAND F. GORDON, OF CORSICANA, TEXAS.

SWITCHING DEVICE.

987,294.

Specification of Letters Patent.

Patented Mar. 21, 1911.

Application filed June 26, 1909. Serial No. 504,535.

To all whom it may concern:

Be it known that I, HOLLAND F. GORDON, a citizen of the United States, residing at Corsicana, in the county of Navarro and 5 State of Texas, have invented certain new and useful Improvements in Switching Devices, of which the following is a specification.

This invention relates to certain new and 10 useful improvements in switch operating mechanisms.

The object of my invention is to provide a manually operated mechanism by means of which a switch can be thrown.

15 Another object is to provide a switch throwing device that can be operated from the car.

With these and other objects in view, the present invention consists in the combination 20 and arrangement of parts as will be herein-after more fully described and particularly pointed out in the appended claim, it being understood that changes in the specific structure shown and described may be made 25 within the scope of the claim, without departing from the spirit of the invention.

In the drawings forming a part of this specification and in which like numerals of reference indicate similar parts in the several views, Figure 1 shows a top view of a track section, provided with my throwing mechanism, the switch being shown as closed, Fig. 2 shows a top view disclosing the switch as open, Fig. 3 shows an enlarged 35 detached detail of the cam head, Fig. 4 shows a front view of a fragmentary portion of a street car showing the position of the throwing rod, Fig. 5 shows a fragmentary portion of the upper end of one of the 40 throwing rods, and the detachable push cap as used in my invention; Fig. 6 shows a side elevation of one of the throw rods, Fig. 7 shows a fragmentary portion of the base plate and the push cap in depressed position.

45 My invention is particularly adapted to be used in connection with trolley and other street cars, and in Fig. 1 the numeral 15 designates the rail, supported upon the ties 16.

50 The rails leading from the switch are marked 14, while the two switch points are marked 17 and 17'. The ends of these switch points 17 and 17' are secured to the bridle bar 18, carrying the pivot pin 19 to

55 which is secured the ends of the sway bar 20, this bar being held to the pivot 21 fixed

to one of the ties 16. At its forward end this sway bar is provided with the cam head 23 having the oppositely positioned securing ears 24 by means of which this cam is secured to the sway bar. A bolt 25 passes through the ears 24 to fix this cam head to the end of the sway bar. The cam head is in the form of a flat metal plate having outwardly flaring edges, so that the forward 65 end of the cam head is very much larger than the rear portion which abuts against the forward end of the sway bar. The oblique edges 27 of the cam head are provided with the upwardly extending flanges 28 so 70 that a V-shaped groove is formed within the upper face of this cam head.

The car is equipped with a throwing mechanism so arranged that in contacting with the cam head, the sway bar will be 75 rocked from side to side to actuate the switch point to open and close the switch.

To the under forward portion of the platform A forming a part of a suitable car is secured the base plate 34 having two side 80 openings 35. Secured in alignment with the base plate 34, is a flat sheet metal bracket comprising the flat center portion 45 from which extends obliquely upward the side members 36 which terminate in the securing 85 plates 37 provided with the bolts 38 by means of which this bracket is secured to the under surface of the car platform. Near the forward edge the bracket portion 45 is provided with the guide openings 44, and 90 positioned obliquely to the rear of these openings 44, are the said side members 36.

Held within the openings 35 of the base plate 34 and within the openings 44 of the center portion 45, are two similar approximately J-shaped throw rods, comprising the major stem portions 32, the transverse bottom portions 28 and the upwardly extending minor portions 30 which are held parallel to the major stem portions 32 as shown. The 100 stem portions 32 and 30 are provided with the bolt openings arranged to receive suitable bolts 12 which pass through openings, within the striker head 11, each throw rod being provided with one of these striker heads. The edges of the striker heads are rounded and these two striker heads 11 are obliquely held with their forward edges converging toward one another as clearly shown. Each throw rod 32 is provided near the upper end 110 with a circumscribing stop collar 33 while each throw rod 30 is provided near its upper

end with a stop collar 27. Held about these major rod portions 32 are the helical springs 36' which at their upper ends work against the stop collars 33, so that these throw rods 5 are held in yielding spaced relation to one another. These rod sections 32 are of such a length, that the ends lie flush with the floor of the car, the openings 35 and 35' within the bottom of the car being somewhat larger 10 than the diameter of the rod stems 32. The striker head 11 determines the upward position of these throw rods as these striker heads contact with the lower under face of the bracket portion 45. Extending from 15 the central portion 45 of the bracket is the brace rod 9 having the securing ears 8 and 8' provided with suitable bolts so that these brace rods may be secured to the under surface of the platform. The car at each end 20 is provided with two such throw rods. In connection with these throw rods, I use a push cap comprising the tubular sleeve 39 ending above in the head 40 which is provided with the corrugated surface to be 25 firmly engaged with the foot of the operator.

The operation of my device is very simple. If the sway bar is in the position indicated in Fig. 1, and the operator decides to take the siding 14, he would place the sleeve of 30 the push cap upon the throw rod to the right and force the rod down on the tension springs 36'. The downward movement of the throw rod would be checked when the cap 40 comes in contact with the floor of 35 the car in which position the striker head will be directly in alignment with the V-shaped slot within the cam head, as, the striker head is at all times in the path of these throw rods. As these striker heads 40 are obliquely positioned, as they pass through the slot within the cam head, the sway bar is actuated to carry the switch points to their opposite positions and thus open the main track to the siding.

45 The openings 35' are of such a size that the tubular sleeve 39 will freely move therein. As a further check to the downward movement of the throw rods, I have provided the stop collars 27 described as secured 50 to the minor rod portion 30. These collars contact with the upper face of the bracket, so that these throw rods cannot be displaced.

Should it be desired to send the car fol-

lowing down the main line, the operator 55 would depress the throw rod so as to throw the sway bar into its original position. The throw rods can only be operated by means of the push cap which as has been said is inserted within the socket surrounding the 60 throw rods. By this means there is no likelihood of the throw rods being accidentally depressed at any time, to improperly throw the switch.

My switch throwing mechanism in no way 65 interferes with the operating or driving mechanism of the car proper, and this can also be said of the switch throwing mechanism which permits the switch being thrown in addition by an ordinary switch stand 70 mechanism.

The operating mechanisms as embodied in my invention are simple of construction, are readily accessible so that repairs can be easily made, and are positive in their operation. The throw rods as shown are held in yielding spaced relation, and the push cap 75 can be readily replaced from one rod to the other. The construction, further in no way detracts from the sightly appearance of the 80 vehicle.

What is claimed is:

In combination with a pivotally held sway bar, and cam heads secured to said bar, of two J-shaped throw rods secured to a car, 85 a bracket depending from the car for guiding said throw rods and for holding the same in a vertical position, collars forming a part of the major stem portions of the throw rods, stop collars forming the ends of the 90 short members of said throw rods, and helical springs encircling the major portions of the throw rods and disposed between the collars forming a part of the same and the lower portion of the bracket for holding the 95 said throw rods in an elevated position, the said stop collars forming the ends of the short members of the throw rods thereby limiting the downward movement of the latter, for engagement with the pivotally held 100 sway bar.

In testimony whereof I affix my signature, in the presence of two witnesses.

HOLLAND F. GORDON.
